US00D809437S

(12) **United States Design Patent** (10) **Patent No.:** **US D809,437 S**
Sugiyama et al. (45) **Date of Patent:** **** Feb. 6, 2018**

(54) **TRIPOD TYPE CONSTANT VELOCITY JOINT**

(71) Applicant: **NTN CORPORATION**, Osaka (JP)

(72) Inventors: **Tatsuro Sugiyama**, Shizuoka (JP); **Hiroaki Makino**, Shizuoka (JP)

(73) Assignee: **NTN CORPORATION**, Osaka (JP)

(**) Term: **15 Years**

(21) Appl. No.: **29/553,585**

(22) Filed: **Feb. 3, 2016**

(30) **Foreign Application Priority Data**

Aug. 3, 2015 (JP) 2015-017252

(51) **LOC (11) Cl.** **12-16**

(52) **U.S. Cl.**

USPC **D12/159**

(58) **Field of Classification Search**

(57) **CLAIM**

The ornamental design for a tripod type constant velocity joint, as shown and described.

DESCRIPTION

FIG. 1 is a front view of a tripod type constant velocity universal joint, showing the new design, a rear view being a mirror image;

FIG. 2 is a top view thereof, a bottom view being a mirror image;

FIG. 3 is a right side view thereof;

FIG. 4 is a left side view thereof;

FIG. 5 is a cross-sectional view taken in the direction of 5-5 in FIG. 4;

FIG. 6 is a cross-sectional view taken in the direction of 6-6 in FIG. 1;

FIG. 7 is a cross-sectional view taken in the direction 7-7 in FIG. 1;

FIG. 8 is an enlarged left side view of the tripod type constant velocity universal joint; and,

FIG. 9 is an enlarged cross-sectional view taken in the direction of 9-9 in FIG. 1.

1 Claim, 9 Drawing Sheets
